(57) **CLAIM**

The ornamental design for a display screen or portion thereof with graphical user interface, as shown and described.

DESCRIPTION

FIG. 1 is a front view of a display screen or portion thereof with graphical user interface in a first state of use;

FIG. 2 is a front view of the display screen or portion thereof with graphical user interface in a second state of use; and, FIG. 3 is a front view of the display screen or portion thereof with graphical user interface in a third state.

The appearance of the transitional image transitions between the images is shown in FIGS. 1-3. The shading is shown to illustrate a contrast of appearance and forms no claim to color, material, texture, or finish. The subject matter in this patent includes a process or period in which an image changes into another image. This process or period forms no part of the claimed design.

The broken lines in the figures show a display screen or portion thereof and form no part of the claimed design.
